RECIPROCATING BED FOR PRINTING-MACHINES.

1,258,949.

Specification of Letters Patent. Patented Mar. 12, 1918.

Application filed October 19, 1914. Serial No. 867,329.

To all whom it may concern:

Be it known that I, WALTER C. SCOTT, a citizen of the United States, and a resident of Plainfield, in the county of Union and State of New Jersey, have invented certain new and useful Improvements in Reciprocating Beds for Printing-Machines, of which the following is a specification.

The present invention relates generally to reciprocating form beds for printing machines, and has more particularly reference to the materials of which said beds are composed.

It is well known in the art of printing that the speed of the modern flat bed press is governed almost entirely by the ease and facility with which the reversing action of the bed may be accomplished; and that the weight of the bed is one of the factors that interferes with its quick and easy reversal.

As is well known in the art, the form from which the printing is done, and which is carried on the type bed, has generally a slightly uneven surface, and this is true whether it is entirely made up of type, or wholly of illustrations, or of both. Considerable work, therefore, known as "making-ready" must be done to overcome this unevenness in the form so that the proper effect may be obtained in the printed product. The usual method of "making-ready" is to attach to the impression surface at points opposite the defective places in the form an amount of packing sufficient to relieve the pressure where the form prints too heavily or to increase it where the form prints too lightly. To do this without producing in the impression conspicuous lines marking the points at which pressure was increased or decreased, is a matter of considerable skill, especially in "making-ready" illustrations, as the ordinary type bed of a press is usually so rigid that the printed product will show the effect of any thickness added to the impression surface even when it is as slight as that of tissue paper.

In studying the above described disadvantages of present day type beds, which are generally made of iron or a mixture of iron, and in endeavoring to reduce the weight and to provide a form supporting surface that will be substantial and at the same time of a perceptibly ductile or malle-

able character, so as to accommodate itself in some degree to the inequalities of the form, tests have been made that establishes the fact that making a type bed of aluminum or an alloy thereof represents a great advance in the art, because the substitution for the heavier metal of a metallic type bed made of much lighter material admits of the bed being reversed at a higher rate of speed, with less shock and, at the same time, the metal is peculiarly adapted to equalize to some extent the differences in the impress that are caused by inequalities in the form and in the impression surface.

Accordingly, the present invention resides in making the reciprocating bed of a metal which is lighter than iron and which is perceptibly ductile or malleable so as to equalize the impression contact and in making some or all of the wearing surfaces of the bed harder than the body of the bed.

Other features will appear as the specification proceeds.

In the accompanying drawings the invention is illustrated in several concrete and preferred forms, from which forms, however, changes in construction may be made without departing from the legitimate and intended scope of the invention.

In said drawings:

Figure 1 is a longitudinal sectional view of a reciprocating bed embodying the invention.

Fig. 2 is a view similar to Fig. 1 showing a modified form of the invention.

Fig. 3 is a transverse sectional view on the line 3-3 of Fig. 1 showing a still further modification of the invention.

Similar characters of reference indicate corresponding parts in the several views.

1 indicates the body portion of a reciprocating bed provided with the customary longitudinal and transverse webbing or ribs 2 and 3. This body portion is made of a metal having the double characteristic of being lighter than iron and of being perceptibly ductile or malleable so that it will have a tendency to equalize the differences in the impress that are caused by inequalities in the form and impression surfaces.

The metal used for the body portion of the bed is aluminum or an alloy thereof, such as may be produced for instance by copper and aluminum. Some or all of the

wearing surfaces of the bed are suitably hardened. For instance, an iron or steel sheathing 4 may cover the top surface on which the type or form rests. This sheathing may be secured to the bed in any suitable manner. In Fig. 1 a stationary clamp 5 and an adjustable clamp 6 are utilized. In Fig. 2 the covering 4 is welded, or electroplated to the bed, or applied thereto by the atomizing blast process. In Fig. 3 the covering is secured to the bed by screws 7. The thickness of the covering 4 should be as light as possible so as not to detract from the equalizing function of the aluminum. So also the ribs or webs 2 and 3, which usually run on roller bearings, may be shod with steel or iron etc. as indicated at 8.

Beds of this type are usually provided with longitudinal bearers at their side edges which engage corresponding bearers on the cylinder. In the present embodiment of the invention these bearers may likewise be made of steel or iron and may be secured to the bed in any suitable manner.

25 1. What is claimed, is:

1. A reciprocating form bed for printing machines composed of a metal which has the double characteristic of being lighter than iron and being perceptibly ductile or malleable and having its type surface harder than the body thereof.

2. A reciprocating form bed for printing machines composed of a metal which has the double characteristic of being lighter than

iron and of being perceptibly ductile or malleable, said bed having wearing surfaces harder than the body thereof. 35

3. A reciprocating form bed for printing machines composed of aluminum or an alloy thereof and having its type surface harder than the body thereof. 40

4. A reciprocating form bed for printing machines composed of aluminum or an alloy thereof, said bed having wearing surfaces harder than the body thereof. 45

5. A reciprocating form bed for printing machines composed of a metal which has the double characteristic of being lighter than iron and of being perceptibly ductile or malleable, longitudinal bearers on the upper side edges of the bed and ribs on the under surface of the bed, said bearers and ribs having a surface which is harder than the body of the bed. 50

6. A reciprocating form bed for printing machines composed of aluminum or an alloy thereof, longitudinal bearers on the upper side edges of the bed and ribs on the under surface of the bed, said bearers and ribs having a surface which is harder than the body thereof. 55

Signed at Plainfield, in the county of Union and State of New Jersey this 16th day of October A. D. 1914.

WALTER CHARLES SCOTT.
